R. K. CARSON

PLATE PRINTING MACHINE

Filed Nov. 17, 1924

UNITED STATES PATENT OFFICE.

ROY K. CARSON, OF DETROIT, MICHIGAN, ASSIGNOR TO WILLIAM J. CARSON, OF DETROIT, MICHIGAN.

PLATE PRINTING MACHINE.

Application filed November 17, 1924. Serial No. 750,353.

This invention relates to the production of half-tone plates for printing pictures and other designs, and its object is to provide means whereby high grade plates may be produced by comparatively unskilled operators and at comparatively low cost and wherein plates may be produced with clear high-lights and well defined tone effects.

This invention comprises a support and a pair of screens movably mounted thereon so that these screens may alternately occupy a definite operative position, and a plate holder adapted to be so moved as to carry a sensitized plate into contact with either of said screens or into contact with a negative which is in contact with one of said screens.

It also consists in one of the screens being formed with heavier lines than the other so that the areas of the sensitized plate affected by the light passing therethrough will be smaller, the two plates being relatively adjustable so that the same areas of the sensitized plate will be affected by the light passing through between the lines of both of the screens.

It further consists of the details of construction illustrated in the accompanying drawing and particularly pointed out in the claims.

In the accompanying drawing, Fig. 1 is a perspective view of this improved printing device. Figs. 2 and 3 are elevations of adjustable bearings adapted for this printing device. Fig. 4 is a central longitudinal section of the holder for the sensitized plate.

Similar reference characters refer to like parts throughout the several views.

It is desirable that those areas of half-tone plates which are to print the high-lights should be provided with fine, closely spaced points or dots adapted to contact with the inking rolls in order to prevent these areas being filled with ink, which would result in dense smudges in the pictures being printed. Such engraved plates can be produced with this present machine by placing a negative between the sensitized metal plate and an unruled perfectly transparent pressure plate after the sensitized plate has been exposed to rays of light passing through a ruled screen, and after such second exposure and developing a plate will be obtained which closely resembles a regular half-tone plate. For many purposes,

such a plate will give excellent proofs and will stereotype well. However, to those skilled in the art, such a plate lacks much in the middle tones that can only be brought out with a second screen exposure, which keeps the shadows well graded and open and still permits strong developing in the high-lights for the purpose of contrast where tones such as white skies are desired. In this second process employing two exposures, the dots are clear and sharp while in the first they are usually clear in the high-lights and closed or smudged in the shadows.

The present process must be distinguished from the usual pre-grained plate methods and single combined exposures of screen and negatives which give little more than a flat or smudged reproduction of the original, and either over-expose the shadows or leave very weak high-light dots (if any dots) thereon. The principal advantages of the present invention are that the metal plate need not be grained before coating with a sensitized enamel; that the first screen fixes the high-lights firmly while the second screen brings up the tones; that the larger openings in the second screen speed up the second exposure; that the regular camera negatives with their original tones permit the passage of light through the second screen to the metal plate, thus favoring tone values; and that the process greatly reduces the time and expense of plate production.

The case 1 shown in the drawing may be of any desired construction, being shown with neither bottom nor top but provided with two partitions 2 (shown in dotted lines in Fig. 1). Mounted on the sides 3 are the bearings 4 for the coarsely ruled screen 5 which is preferably of properly ruled glass, the lines being heavy so that the spaces between are small, and the screen being mounted in a metal frame 6 provided with pintles 7 which are rotatable in the blocks 8 shown in Fig. 3. The block at each end of the plate is vertically slidable in a guide 9, being pressed up by means of a spring 10 and held down by a screw 11 which permit accurate vertical adjustment.

The guide 9 is mounted on a base 12 which is secured onto a bar 13 by means of screws 14 which pass through longitudinal slots

- in this guide. The bar 13 carries lugs 15 in which screws 16 are mounted and it is apparent that upon loosening the screws 14 that this base and the pintle 7 can be moved longitudinally of the side 3 of the case to which this particular bar 13 is attached by means of screws 18. Any other desired type of bearing which permits of longitudinal and vertical adjustment may be employed.
- 10 The screen 20 is similar in construction and in mounting to the screen 5 and the spacing of the lines of the screen is the same, but the lines are not so deep or heavy as those of the screen 5. Its bearings are numbered 21. While I have described the screen 5 as being on the left and the screen 20 on the right, the positions of these screens may be interchanged if desired.
- 15 In order to provide a proper support for the screens I may secure a heavy plate 22 of clear glass to the sides 3 and partitions 2 which is sufficiently strong to withstand the pressures which may be applied thereto. Any other desired support may be employed.
- 20 Attached to the outer surface of the rear side 3 are two upright bars 24 which carry the bearings 25 for the shaft 26. These bearings are more clearly shown in Fig. 2 and embody a guide member 28 attached to the member 24 by means of screws 29. A block 30 constitutes the bearing for the shaft 26 and this block is pushed upward by the spring 32 against the adjusting screw 33.
- 25 Mounted on the shaft 26 is a flat plate holder 34 to which is attached a strip 35 of metal by means of the screws 36, more clearly shown in Fig. 4. The inner edge of this strip 35 is slightly beveled so as to constitute a good engaging surface for the beveled edge of the sensitized plate 37. This plate has its opposite edge engaged by means of a similar metal strip 38 which is attached directly to a cross bar 39 by means of screws 40 which pass through the spacing blocks 41.
- 30 The holder 34 is formed with V-shaped grooves 43 in which these blocks 41 are slideable, and the cross bar 39 carries the small rods 44 which are slideable in a stationary bar 45 and these rods 44 carry the springs 46. The cross bar 45 is secured in position by means of the bolts 47 and wing nuts 48, the bolts being slideable in the grooves 43 in the holder 34. The springs 46 have sufficient strength to so press the strip 38 against the sensitized plate 37 as to hold it sufficiently rigidly for all practical purposes. Because of this spring construction, the sensitized plates 37 can be quickly positioned on the holder 34 and can be as readily removed, but when plates of a different size are to be printed, the wing nuts 48 are slackened and the cross bar 45 moved to proper position for the new plates.
- 35 The case 1 is provided with pintles 50 which are rotatable in the uprights 51 car-

ried by the base frame 52, and the light for the printing is preferably obtained from an arc light 53.

The mode of using this printing device is as follows: The sensitized plate 37 is mounted on the holder 34 as shown and the screen 5 with the fine openings is folded down against the support 22, whereupon the sensitized plate is brought down against the screen 5 and held in position in any desired manner, the spring hooks 54 shown in Fig. 4 which engage the eyes 55 secured to the front 3 of the case being particularly adapted for this purpose, although any other desired means may be employed. The case is then rotated until the plate 37 is at right angles to the beam of light from the arc light 53 which enters the bottom of the case and passes through the screen 5 to the sensitized plate 37. After an exposure of about two minutes the case is turned to normal position, the spring hooks 54 are released, the holder 34 is swung up, the screen 5 is swung back and the screen 20 is swung into its position. Thereupon, the photographic negative or drawing is placed upon the screen 20 and the sensitized plate is swung down against it, the screws 33 being turned back if necessary to provide for this additional thickness of the negative or drawing. When the negatives are in the form of celluloid films, no such adjustment is necessary. The case is then again swung to printing position and light is permitted to pass through the screen 20 and the negative to the sensitized plate 37. When not in use, the screens are swung back into the case.

The sensitized plate is preferably so coated than an exposure of five minutes through the second screen is sufficient to produce the desired results.

After developing, the positive print will seem to rest in a field of fine dots and no details of the subject will be lost as the picture is built on the dots rather than being broken up by them as is the case with half-tone reproductions of line subjects. These fine dots not only shade the subject but eliminate the necessity of deep etching. Half-tone and line plates can be completely produced by this process in twenty minutes, it being assumed that properly sensitized plates and negatives are on hand for the work. These plates are unmounted and are adapted for newspaper stereotyping. It is not necessary for the engravers to rout out the high-lights that have been broken down in the developing or etching as is the case when the weak dots which occur on reproductions of white surfaces are destroyed. In the present process all the high-lights are firmly fixed before the grading of the heavier tones during the second exposure, and these high-lights can therefore be made as light or as heavy as desired by controlling the

time of the first exposure and the second exposure can be timed to give either hard or soft outlines of the picture as desired. There are, therefore, four time limits, two for each 5 exposure, which give the operator entire control of the tones and contacts. Heretofore, this had to be done by chemical manipulations which require considerable time and great skill.

10 While the screens can be ruled with great accuracy, the mounting may not always be so accurate, and the bearings shown in Fig. 3 are therefore desirable, for with them the screens can be adjusted relative to each other 15 so that their lines will occupy absolutely the same positions when the screens are swung to operative position.

I claim:

1. In a device of the class described, the 20 combination of a support, a pair of screens pivotally mounted thereon and adapted to be swung alternately to the same position, and a carrier for sensitized plates adapted to be moved to carry such plates into contact with 25 said screens in succession, the lines on the two screens being similarly spaced and the screens and plate carrier being so mounted that the lines of both screens will affect the same portions of the sensitized plates and a 30 source of light adapted to produce rays which pass unobstructed by lenses through said screens to the sensitized plate.

2. In a device of the class described, the 35 combination of a support, a pair of screens pivotally mounted thereon and adapted to be swung alternately to the same position, a carrier for sensitized plates adapted to be moved to carry such plates into contact with said screens in succession, and adjustable 40 bearings for one of said screens the lines on the two screens being similarly spaced and the screens and plate carrier being so mounted that the lines of both screens will affect the same portions of the sensitized plates and a source of light adapted to produce rays which pass unobstructed by lenses through said screens to the sensitized plate.

3. In a device of the class described, the 50 combination of a support, a pair of screens pivotally mounted thereon and adapted to be swung alternately to the same position, a carrier for sensitized plates adapted to be moved to carry such plates into contact with said screens in succession, and adjustable 55 bearings for one of said screens and the plate holder the lines on the two screens being similarly spaced and the screens and plate carrier being so mounted that the lines of both screens will affect the same portions 60 of the sensitized plates and a source of light adapted to produce rays which pass unobstructed by lenses through said screens to the sensitized plate.

4. In a device of the class described, the 65 combination of a support, a pair of screens

pivots mounted thereon and adapted to be swung alternately to the same position, a carrier for sensitized plates adapted to be moved to carry such plates into contact with said screens in succession, pivots for said 70 support, and a source of light positioned to project rays of light through the screens as the support is turned on its pivots the lines on the two screens being similarly spaced and the screens and plate carrier being so mounted that the lines of both screens will affect the same portions of the sensitized plates and a source of light adapted to produce rays which pass unobstructed by lenses through said screens to the sensitized plate. 75

5. In a device of the class described, the combination of a support embodying a glass plate, a pair of screens pivotally mounted thereon and adapted to be swung alternately into contact with said glass plate, and a carrier for sensitized plates pivoted on the support and adapted to be swung to carry such plates into contact with said screens in succession, the lines on the two screens being similarly spaced and the screens and plate 80 carrier being so mounted that the lines of both screens will affect the same portions of the sensitized plates and a source of light adapted to produce rays which pass unobstructed by lenses through said screens to 85 the sensitized plate.

6. In a device of the class described, the combination of a support, a pair of screens pivotally mounted thereon and adapted to be swung alternately and independently of each other to the same position, a carrier for sensitized plates adapted to be moved to carry such plates into contact with said screens in succession, the spaces between the lines of one screen being smaller than the 90 spaces between the lines of the other the lines on the two screens being similarly spaced and the screens and plate carrier being so mounted that the lines of both screens will affect the same portions of the sensitized plates and a source of light adapted to produce rays which pass unobstructed by lenses through said screens to 95 the sensitized plate.

7. In a device of the class described, the combination of a support, a pair of screens pivotally mounted thereon and adapted to be swung alternately to the same position, and a carrier for sensitized plates adapted to be moved to carry such plates into contact with said screens in succession, the 100 spaces between the lines of the first screen employed being smaller than those between the lines of the second screen the lines on the two screens being similarly spaced and the screens and plate carrier being so mounted that the lines of both screens will affect the same portions of the sensitized plates and a source of light adapted to produce rays which pass unobstructed by lenses through 105 said screens to the sensitized plate.

8. In a device of the class described, the combination of a support, a pair of transparent screens mounted thereon, a carrier for sensitized metal plates adapted to be moved to carry such plates into contact with such screens in succession, the lines of said screens being spaced the same distance apart but the lines of one screen being wider than those of the other, and a source of light adapted to produce rays which pass unobstructed and unchanged through said screens to the sensitized metal plate. 10

ROY K. CARSON.
